CLOCK WITH ATTACHMENT

John Gorrien, Minneapolis, Minn.

Application February 12, 1937, Serial No. 125,462

7 Claims. (Cl. 200—37)

This invention relates to a clock with attachment useful for a variety of purposes, but as disclosed herein more especially adapted to the purpose of notifying or reminding persons, such as 5 hotel clerks, of the time at which to perform some particular service, as, for example, to call a patron of a hotel at a previously stated time.

Hotel clerks have many different duties among 10 which are the noting of instructions each night from many hotel patrons that the patrons are to be awakened next morning at stated times, some, say, at 7:00 a. m., some at 7:15, some at 8:00, etc. The clock with attachment herein presented has been especially designed to notify or 15 remind hotel clerks at set times when calls of patrons are to be made, although it is to be understood that the device of the invention can be employed for a number of different purposes, as for instance, to notify or remind a person at 20 a predetermined appointed time when any duty or act is to be performed.

An object of the invention is to provide a clock with attachment adapted to the purpose of notifying or reminding persons of the time when 25 services or acts are to be performed, and which clock with attachment will be of novel and improved construction.

A further object is to provide a device of the 30 present character wherein will be incorporated various improved features and characteristics of construction novel both as individual entities of the device and in combination with each other.

A further object is to provide a clock with attachment of quite simple construction which will 35 by concurrent reference to both the hour and the minute hands of a clock be adapted to notify or remind persons at accurate, predetermined times when services or acts are to be performed.

And a further object is to provide a clock with 40 attachment for notifying or reminding persons of the time when services or acts are to be performed which will include adjustable mechanism through the instrumentality of which the exact time, or minute, at which the clock with attachment is intended to give notification to or remind a person of the time when a service or act 45 is to be accomplished can be accurately controllably varied.

With the above objects in view, as well as 50 others which will appear as the specification proceeds, the invention comprises the construction, arrangement and combination of parts as now to be fully described and as hereinafter to be specifically claimed, it being understood that the disclosure herein is merely illustrative and in-

tended in no way in a limiting sense, changes in details of construction and arrangement of parts being permissible so long as within the spirit of the invention and the scope of the claims which follow.

In the accompanying drawings forming a part of this specification,

Fig. 1 is a front elevational view of a device or clock with attachment made according to the invention;

Fig. 2 is a horizontal sectional view, taken substantially on line 2—2 in Fig. 1;

Fig. 3 is a detail view disclosing the manner in which the clock with attachment of Figs. 1 and 2 is by concurrent reference to both the hour and the minute hands of said clock adapted to notify or remind persons of the time when services or acts are to be performed;

Fig. 4 is a sectional view, taken substantially on line 4—4 in Fig. 3;

Fig. 5 is a view corresponding generally with the disclosure of Fig. 3, but including modified or adjustable mechanism for varying the times, or minutes, at which a clock with attachment made according to the invention can be made to notify or remind persons of the time when services or acts are to be done;

Fig. 6 is a sectional view, taken substantially on line 6—6 in Fig. 5;

Fig. 7 is a fragmentary elevational view of the 30 modified or adjustable mechanism of Figs. 5 and 6 as it would appear from the right hand side of said Fig. 6.

Fig. 8 is an enlarged elevational view of one of 35 duplicate jacks or plugs which the device employs;

Fig. 9 is an elevational view of the current conveying portion or element and the spreader member of the jack or plug of Fig. 8 with the insulating finger piece of said jack or plug removed therefrom;

Fig. 10 is an elevational view of the spreader member of the jack or plug removed from the current conveying portion or element of Fig. 9; and

Fig. 11 is an end elevational view of the jack or plug of Fig. 8 as it would appear from the top side of the sheet.

The disclosure as made is of an electric clock 15, although it will become apparent hereinafter that the clock employed could be mechanically, or spring, driven. The clock frame is as illustrated of insulating material. A usual case 16 of the clock is secured upon the forward member 17 of the frame as at 18, and said forward member 50 55

11 includes a front surface 19 providing a dial or clock face. A hollow shaft 20 driven by mechanism (not shown) within the case 18 fixedly supports or carries a usual hour hand 21 of the clock, 5 and a shaft 22 within the hollow shaft 20 and driven by mechanism within said case fixedly supports or carries a usual minute hand 23 of the clock. The hour hand 21 and the minute hand 23 bear customary relation to the dial or hand 19. As shown, said hour hand travels 10 over said dial or clock face at location between the minute hand and the dial or clock face. That is, said minute hand is at the outer side of said hour hand. The arrangement is such that at the 15 locations of mounting the hour and the minute hands upon their respective shafts said hour and minute hands are constantly in light rubbing engagement with each other, as denoted at 24. The hour and minute hands are constructed of metal or of other material having capacity to conduct 20 electrical current. The shafts 20 and 22 may be of insulating material, or insulatively supported within the case 16.

An annular member 25 of insulating material 25 is suitably supported, in any convenient manner, as by gluing, or otherwise, upon the front surface of the forward member 17 of the clock frame in surrounding relation to the dial or clock face. The annular member 25 integrally 30 carries an annular flange 26 of reduced thickness which extends inwardly of said annular member. The annular flange 26 is in the plane of the annular member 25 and is arranged adjacent the forward surface of said annular member so 35 that an annular pocket 27, defined by the annular member 25, the annular flange 26 and an annular portion of the front surface of the forward member 17, is provided.

The inner marginal portion of the annular 40 flange 26 integrally supports an inwardly extending annular element 28 arranged in the plane of the annular member 25 and the annular flange 26 and situated adjacent the forward surface of said member 25 and its annular flange 45 26. The annular element 28 is of considerably less thickness than the annular flange 26. A glass cover 29 for the dial or clock face and the 50 clock hands 21 and 23 is of circular conformation, and an annular marginal portion 30 of said glass cover is seated against the inner surface of said annular element 28 adjacent an annular transverse shoulder 31 of the annular flange 26. The marginal portion 30 is secured to the 55 annular element 28 in any convenient manner, as by gluing, or otherwise. The body portion of the glass cover 29 as disclosed bulges outwardly, or forwardly, in direction away from the dial or clock face and the hands 21 and 23. Said dial or clock face is marked in hours and minutes 60 in a well known manner.

Lead wires 32 and 33 from a source (not shown) of electrical energy are secured to the case 16 by means of binding posts 34 and 35. Electrical current carried by said lead wires 32 and 33 65 is adapted to actuate clock mechanism within the case 16 in a manner which, as such, forms no explicit part of the invention. Suffice it to say that through the instrumentality of electrical current carried by the lead wires 32 and 33 70 the hour and minute hands 21 and 23 are driven at intended and proper rates of speed, said minute hand as illustrated being adapted to make one complete revolution while said hour hand is traveling one-twelfth of a revolution.

75 A transformer suitably and conveniently

mounted within the frame of the clock 15 includes a primary 36 and a secondary 37. A lead wire 38 extends from the binding post 34 to one side of the primary 36 and a lead wire 39 extends from the other side of said primary to 5 the binding post 35.

The annular flange 26 upon the annular member 25 includes a series of equally spaced apart openings 40 each with metallic eyelet 41, or other tubular conducting element, arranged 10 therein. The eyelets or tubular conducting elements 41 are disposed concentrically of the shafts 20 and 22. Said eyelets or tubular conducting elements may be spaced apart any preferred distances. As disclosed, there are forty-eight openings 40 each with eyelet or tubular conducting element 41. The outer end of each eyelet or tubular conducting element is enlarged, as at 42, and engages the front surface of the annular member 25 and the annular flange 26. The 20 inner end portion of each eyelet or tubular conducting element lies in the annular pocket 27, and the inner ends of the eyelets or tubular conducting elements terminate in spaced relation to the inner surface of the annular member 25 25 and the front surface of the forward member 17 of the frame of the clock. See Figs. 2 and 4.

An annular member or plate 43 of metal, or of other conducting material, is suitably secured to the inner surface of the annular member 25, as by gluing, or otherwise, and includes an inner, annular marginal portion 44 lying in the annular pocket 27. As disclosed, the annular member or plate 43 and its inner, annular marginal portion 44 are in contiguous relation 35 to the front surface of the forward member 17 of the frame of the clock and in spaced relation to the eyelets or tubular conducting elements 41. The inner, annular marginal portion 44 of the conducting member or plate 43 includes openings 40 45 in substantial alignment with the openings through the eyelets or tubular conducting elements 41, there being an opening 45 corresponding to each eyelet or tubular conducting element. The arrangement is such that the openings 45 are a trifle off-set with respect to the openings or passageways through the eyelets or tubular conducting elements 41. The front surface of the forward member 17 of the clock frame includes openings 46 in alignment with 50 the openings or passageways through the eyelets or tubular conducting elements and in alignment with the openings 45, there being an opening 46 corresponding to each substantially aligning set of openings 40 and 45. 55

The annular member 25 includes an annular channel or concavity 47 therein which suitably houses a lead wire 48. Said lead wire 48 spans the complete circumference of the annular channel or concavity 47, or, stated differently, the 60 lead wire 48 may be continuous.

Conducting strips 49 are disposed in spaced apart relation about the inner surface of the annular flange 26 and are supported upon said annular flange in any suitable and convenient manner, as by gluing, or otherwise. By way of example, there may be four conducting strips 49 spaced at equal distances apart, including a conducting strip adjacent each of "3", "6", "9" and "12" on the dial or clock face. Each conducting strip 49 includes a body portion extending along the annular flange 26 circumferentially thereof and a tail or flange portion 50 of the conducting strip situated in a passageway 51 of the annular member 25 and conductively engaging the 75

continuous or circular lead wire 48. Each passageway 51 extends from the annular pocket 25 to the annular channel or concavity 47. As very clearly shown in the drawings, the conducting strips 49 and their tails or flanges 50 are in spaced relation to the eyelets or tubular conducting elements 41, as well as in spaced relation to the annular conducting member or plate 43 and its inner, annular marginal portion 44.

10 The minute hand 23 is adapted to successively wipe over the body portions of the conducting strips 49 as said minute hand advances, as will be very clear from Figs. 2, 3 and 4. The hour hand 21 has a radial conducting extension 52 secured thereto and including a shaped spring member 53 arranged in the annular pocket 27 and adapted to successively wipe over the eyelets or tubular conducting elements 41 as said hour hand advances. The construction of the shaped spring member 53 desirably is such that there is contact between said spring member and each eyelet or tubular conducting element engaged by the spring member for several, or a few, minutes of time.

25 A buzzer 54, or other signaling, notifying or reminding apparatus, is conveniently situated within the frame of the clock adjacent the transformer and the case 16. A lead wire 55 extends from one side of the secondary 37 of said transformer to the buzzer or signaling apparatus 54. A lead wire 56 extends from said buzzer or signaling apparatus to a binding post 57. The binding post 57 is as illustrated constituted as a screw bolt extending through the forward member 17 of the frame of the clock and through the annular conducting member or plate 43 and entering the annular member 25. Said binding post or screw bolt 57 has conducting engagement with said annular conducting member or plate 43. 30 The screw bolt 57 can assist in supporting the annular conducting member or plate 43 in position and additional screw bolts of the same general character can also pass through the members 17 and 43 and enter the member 25 and assist in 35 supporting, or support, the annular conducting member or plate, as will be understood.

40 A lead wire 58 in electrical engagement at 59 with the continuous or circular lead wire 48 extends from said continuous or circular lead wire to the side of the secondary 37 of the transformer opposite the side to which the lead wire 55 is connected. The annular conducting member or plate 43 is cut away at 60 to allow passage of the lead wire 58 and to be clear of said lead wire.

45 Jacks or plugs of the device, adapted separately to provide conducting connection between any selected one of the eyelets or tubular conducting elements 41 and the annular conducting member or plate 43, are each of construction as clearly illustrated in Figs. 3, 4 and 8 to 11. A U-member of each jack or plug includes closely adjacent, parallel legs 61 connected by a base 62. Each leg 61 is curvilinear in cross section, and the free end portions of said legs 61 diverge slightly. That is, the legs 61 are in slightly 50 divergent relation to each other at their free end portions. Concave parts of the legs 61 face each other and said legs lie in a single plane. The free ends of the legs 61 are at equal distances from the base 62 and adjacent each other, and each of said free ends is of rounded conformation, as indicated at 63. The U-member is in the instance of each jack or plug of resilient metal, or of other resilient conducting material.

75 A spreader member 64 for the legs 61 is seated be-

tween the concave portions of said legs against the base 62. Said spreader member is as disclosed of about one-half the length of the U-member. An insulating finger piece 65 of each of the duplicate jacks or plugs is tightly secured upon the portion of the U-member which houses the spreader member.

The legs 61 of the U-member of each jack or plug employed are adapted to be inserted, selectively, into and through the eyelets or tubular conducting elements 41, into and through the openings 45 in the inner, annular marginal portion 44 of the annular conducting member or plate 43, and into the openings 46 in the frame member 17. The free end portions of the legs 61 of each jack or plug are spread apart to such extent that upon insertion of the rounded ends 63 of said legs into an eyelet or tubular conducting element and into a substantially alining opening each other against their natural resilient tendency 20 to spread. Thus there will be insurance of resilient, pressing engagement of the U-member of each jack or plug with the interior of each eyelet or tubular conducting element 41. Each jack or plug is inserted into a selected eyelet or tubular 25 conducting element until the insulating finger piece 65 of the jack or plug engages the enlarged part 42 of the eyelet or tubular conducting element, as in Fig. 4. The arrangement is such that as the free ends 63 of the legs of a jack or plug 30 are passed beyond an eyelet or tubular conducting element and into a substantially alining opening 45 in the inner, annular marginal portion 44 of the annular conducting member or plate 43, the diverging, free end portions of said legs 35 commence to spread apart, because of release of said diverging, free end portions by said eyelet or tubular conducting element and the natural resilience of the metal of the U-member. By reason of the spreading apart of the legs, resilient, pressing 40 engagement of the jack or plug with the metal of the annular conducting member or plate 43 at the openings 45 in the marginal portion 44 is insured, as will be understood. Off-setting the openings 45 a trifle relatively to the eyelets or tubular conducting elements additionally insures that there will be engagement between the legs and the annular conducting member or plate.

45 When a jack or plug is arranged in an eyelet or tubular conducting element and in a substantially alining opening 45 in the manner as before set forth, the eyelet or tubular conducting element having said jack or plug is obviously conductively connected to the annular conducting member or plate 43 through the instrumentality 50 of the legs 61 of the jack or plug, which legs are in current carrying engagement with both said eyelet or tubular conducting element and said annular conducting member or plate. See Fig. 4.

55 The manner in which the device or clock with attachment operates is simply explained. Supposing it to be intended that a notifying or reminding signal be produced at, say, nine o'clock, for example, a jack or plug is inserted in the manner as stated into the eyelet or tubular conducting element directly adjacent "9" on the dial or clock face. The buzzer will, then, be caused to sound at nine o'clock and at no other time, because electrical connection through said 60 buzzer is also through both the hour and the minute hands of the clock, as well as through the annular conducting member or plate 43 and, separately, through the conducting strips 49. The radial extension 52 will engage said eyelet or 65

tubular conducting element directly adjacent "9" while the minute hand is also in engagement with a conducting strip 49 when and only when said minute hand is at, or fairly close to, "12" on the dial or clock face. Upon engagement of the radial extension 52 on the hour hand 21 with the eyelet or tubular conducting element directly opposite "9" and having a jack or plug therein and also in contact with the annular conducting member or plate 43 while the minute hand 23 is in engagement with the conducting strip 49 adjacent "12" on the dial or clock face, an operating circuit through the buzzer 54 will be made from the secondary 37 of the transformer through the lead wire 55 to said buzzer, thence from the buzzer through the lead wire 56 and the binding post or screw bolt 57 to the annular conducting member or plate 43, thence through the jack or plug in the eyelet or tubular conducting element directly adjacent "9" and this same eyelet or tubular conducting element to the radial extension 52, thence through the hour hand 21 and the minute hand 23 to the conducting strip 49 at "12", and thence through the tail or flange 50 of said conducting strip at "12", the continuous or circular lead wire 48 and the lead wire 58 back to the secondary of said transformer.

In the instance of a signal to be given at any selected time of the clock, the manner of operation is the same as described. For any particular setting of a jack or plug, there is only one of the conducting strips 49 which will be engaged by the minute hand 23 while the radial extension 52 upon the hour hand 21 is in engagement with an eyelet or tubular conducting element having said jack or plug situated therein. In every instance, the signal is given by concurrent reference to both the hour and the minute hands of the clock so that the occurrence of said signal is at an accurate, predetermined time. Obviously, a plurality of jacks or plugs can be simultaneously positioned in different openings of the clock. The operation in the case of each inserted jack or plug will be entirely independent of the operation resulting from the insertion of all other jacks or plugs. That is, insertion of a jack or plug at any opening in the clock causes notifying or reminding operation to occur independently of notifying or reminding operation caused by insertion of jacks or plugs in all other openings in the clock.

Each conducting strip 49 has length so that it is engaged by the minute hand 23 for a few, or several, minutes, and the shaped spring member 53 upon the radial conducting extension 52 is constructed to remain in engagement with each eyelet or tubular conducting element 41 for a few, or several, minutes, as before stated. It will be apparent that each signal will be made discernible at an accurate time, or minute, as intended even though the hour hand and the minute hand may not have accurate setting, within limits, relatively to each other. The spring member upon the radial extension 52 may first engage an eyelet or tubular conducting element 41 with jack or plug set therein, and the minute hand may afterwards engage one of the conducting strips 49 before engagement between the spring member and the eyelet or tubular conducting element has become broken when a signal is to be given, or the reverse may be the case.

While the conducting strips 49 have some length, they are not so long that the minute hand 23 can traverse any space between adjacent conducting strips 49 during the interval the hour

hand is conductively connected with any single eyelet or tubular conducting member 41. Stated differently, the arrangement is such that the minute hand 23 can engage only one of the conducting strips 49 while the hour hand has contact with any one of the eyelets or tubular conducting elements 41.

In Figs. 6 and 7 there is disclosed a construction in all respects like that hereinbefore described, except that the conducting strips, denoted 66, 10 equivalent to the conducting strips 49, are adjustable circumferentially of the annular flange 67, equivalent to the annular flange 26. The adjustment is for the apparent purpose of accurately controllably varying the time, or minute, 15 at which the device is intended to produce a signal. Each conducting strip 66 includes an internally threaded boss 68 slidable in an elongated slot 69 in the annular flange 67, and a set screw 70 is for fixing the corresponding conducting strip 66 at any position to which adjusted along said elongated slot. Each conducting strip 66 has slidable engagement with a tail or flange 71, 20 equivalent to each tail or flange 50 and similarly arranged in the annular insulating member 72, 25 equivalent to the annular insulating member 25.

Attention is called to the fact that each of the entities of the present device which in any instance of use of the device can possibly function or serve as a movable element of any electric switch of said device engages its companion stationary element with a wiping action.

What is claimed is:

1. A switch mechanism comprising a plurality of separate tubular conducting elements, a conducting member in spaced relation to said tubular conducting elements, a conducting plug adapted to be set in any selected one of said tubular conducting elements in engagement therewith and in engagement with said conducting member, a plurality of conducting strips arranged in spaced relation to each other, a movable switch element adapted to successively wipe over said conducting strips, a second movable switch element adapted to successively wipe over said tubular conducting elements, and said switch element when in engagement with one of said conducting strips while said second switch element is in conducting engagement with one of said tubular conducting elements having a plug 35 therein in conducting engagement with said conducting member being adapted to close a circuit.

2. The combination as specified in claim 1, and means for adjusting said conducting strips relatively to said tubular conducting elements. 55

3. A switch mechanism comprising a plurality of separate tubular conducting elements, a conducting member in spaced relation to said tubular conducting elements, a conducting plug adapted to be set in any selected one of said tubular conducting elements in engagement therewith and in engagement with said conducting member, a movable switch element adapted to be successively brought into conducting engagement with said tubular conducting elements, a plurality of conducting strips arranged in spaced relation to each other, a second movable switch element adapted to successively engage said conducting strips, and said second switch element when in conducting engagement with one of said conducting strips while said switch element is in conducting engagement with a tubular conducting element having a plug therein and which plug is in conducting engagement with said conducting member being adapted to close a circuit. 75

4. The combination as specified in claim 3, wherein said conducting member includes spaced apart openings arranged in a circumference and said tubular conducting elements are arranged in an adjacent concentric circumference, there being a tubular conducting element in alining relation to each of said openings.

5. The combination as specified in claim 3, and means for adjusting said conducting strips relatively to said tubular conducting elements.

6. In a switch mechanism, a plurality of separate tubular conducting elements, a conducting member in spaced relation to said tubular conducting elements, a conducting plug adapted to be set in any selected one of said tubular conducting elements in engagement therewith and in engagement with said conducting member, and

a movable switch element adapted to be successively brought into conducting engagement with said tubular conducting elements.

7. In a switch mechanism, a plurality of separate tubular conducting elements, a conducting member in spaced relation to said tubular conducting elements, a conducting plug adapted to be set in any selected one of said tubular conducting elements in engagement therewith, said conducting plug being adapted to traverse the space between the conducting member and the tubular conducting element in which set and to engage said conducting member, and a movable switch element adapted to be successively brought into wiping engagement with external side surfaces of said tubular conducting elements.

JOHN GORRIEN.
